UNITED STATES PATENT OFFICE.

ARTHUR L. THURSTON, OF FREEPORT, NEW YORK, ASSIGNOR, BY MESNE ASSIGNMENTS, TO CURTISS AEROPLANE AND MOTOR COMPANY, INC., OF GARDEN CITY, NEW YORK, A CORPORATION OF NEW YORK.

AIRPLANE RADIATOR.

Application filed May 16, 1921. Serial No. 470,186.

This invention relates to radiators for airplanes and is characterized in that the cells or water passages of the radiator are so arranged upon the structural framework of an element of the airplane as to provide therefor a covering. More particularly the invention relates to "wing type" radiators, i. e., radiators in which the cells or water passages are so organized and related one to the other as to provide a hollow shell of wing profile through the hollow of which the airplane wing is adapted to extend.

Several forms of wing type radiator have heretofore been proposed. No one, however, in so far as I am aware, has succeeded in perfecting a wing type radiator in which ample provision is made for cooling the liquid agent without adding materially to the head resistance of the wing or lessening its lift co-efficient. Experiments have been conducted with radiators involving the use of flat plates between which the cooling agent is circulated in the form of a thin sheet or film. Wing type radiators have also been proposed in which the cooling agent is circulated thru cells cooled by the passage of air thereover. The former type of radiator is inefficient and impractical (when constructed as a wing type radiator) due to the necessarily large area required to cool the cooling agent whereas the latter form is inefficient because of the decrease in lift and increased resistance resulting from the passage of the air thru the wing. For efficiency in cooling, however, the latter form of radiator, i. e. cellular, is preferred. Accordingly the radiator herein disclosed is cellular (in that a plurality of water passages are provided) and at the same time is so organized and arranged as to offer a minimum of resistance; is light compared to former types of radiators; is constructed as a composite part of the airplane wing, (it may be constructed as a covering for or composite part of an element of the airplane other than the wing) and its construction is such that the lift of the wing is in no way impaired. Thus characterized the radiator of the present invention may be said to offer practically no resistance whatsoever in and of itself and may be embodied in an airplane structure without requiring a deformation of any part thereof.

In the drawings, wherein like characters

of reference designate like or corresponding parts,

Fig. 1 is a front end elevation of an airplane, partly broken away, showing the preferred relative arrangement of the radiator, wings and body,

Fig. 2 is a plan view of so much of the airplane as is illustrated in Fig. 1,

Fig. 3 is an enlarged sectional view showing in detail the construction of the radiator and its relation to the airplane wing,

Fig. 4 is a section on the line 4—4 of Fig. 3, and

Fig. 5 is a fragmentary sectional view illustrating a slight modification.

In the embodiment of the invention selected for illustration, the radiator is shown as comprising separate radiator sections, each section of which is designated in its entirety as 10. Preferably, though not necessarily the sections 10 are arranged on opposite sides of the fuselage or body 11 of the airplane and are constructed as a composite part of the wings 12 which, in the embodiment shown, extend out right and left from the fuselage 11 and constitute the lower wings of a biplane structure. The upper wings (but one of which is illustrated, see Fig. 2) are designated as 13, and the power plant, of which the radiator is an accessory, is designated as 14 and is enclosed in the forward end of the body in such manner that the streamline contour of the body is in no way destroyed.

The wings of the airplane may be of any conventional construction and may be either internally or externally trussed since the construction of the radiator is such that the internal structure of the wing may be of any character desired. In Fig. 4 wing beams 15 and 16 are shown which, together with ribs 17 constitute a skeleton framework over which the covering for the wing is drawn. Except in the vicinity of the fuselage, where the wing covering is formed by the radiator sections 10, any character of covering such as fabric or veneer may be used.

The radiator sections 10 are identical in construction. Each comprises a forward header 18 and a rear header 19, the former being incorporated in the wing structure adjacent to the leading edge and, if desired, may supplant the nose strip of the wing throughout that portion of the length of the wing

constructed as a radiator section. The rear header 19 may supplant the trailing edge strip of the wing though in the embodiment illustrated the header 19 is shown fastened 5 against the rear face of the rear wing beam 16.

To provide for the circulation of the cooling fluid from one to the other of the headers of the radiator, a plurality of radiator cells 10 or water passages 20 are so arranged upon the outer surfaces of the wing structure as to join the headers, the cells or water passages 20 being preferably arranged in parallelism and so disposed as to provide an imperforate covering for a given portion of the wing. In constructing the cells a flat plate 21 is fastened to the wing framework and a corrugated plate 22 is fastened on the outside face of the flat plate 21. The corrugations 20 formed in the plate 22 extend in a fore and aft direction and are provided upon both surfaces of the wing. At their forward ends the cells or water passages 20 are open to the header 18 as at 23 and at their rear 25 ends are open to the header 19 as at 24. Thus organized the cooling agent is free to circulate uniformly from one to the other of the headers thru the total number of cells or water passages and during such circulation is properly cooled to offer the desired cooling effect on the motor.

In Fig. 2 the connections between the radiator sections 20 are designated as 25 and the connections between the radiator sections 35 and the motor 14 are designated as 26. The total number of connections are confined to the interior of the fuselage and are thus entirely removed, as are the headers, from the line of air rush incident to flight.

40 A radiator thus constructed provides ample exposed area for cooling purposes and at the same time, since the cells are arranged side by side, affords a suitable imperforate covering for the wing. The head resistance 45 which a radiator thus constructed offers is negligible and its construction exceptionally light. Moreover, there is no decrease whatsoever in the lift of the wing since the air in reacting on the wing surface is prevented from passing thru the wing.

50 In the modification illustrated in Fig. 5 the corrugated plates 22 are duplicated on the inner faces of the flat plates 21 and openings 27 are formed in the leading and trailing edges respectively of the wing to provide for the circulation of air over the inside corrugations or cells. Such an arrangement 55 may be under certain conditions desirable since the area of the radiator can be proportionally decreased.

In accordance with the patent statutes I have set forth in the specific manner required thereby one complete embodiment of my invention, but it is understood that this 65 is only for illustrative purposes and that the

invention is capable of assuming other forms than that illustrated and that the claims hereto annexed are not to be limited to the specific devices illustrated, except as is specifically recited therein. Obviously, if desired, the radiator may be given a shape in cross-section other than that of an airplane wing, and may be, if desired, so constructed as to provide an outer covering or hollow shell through which a structural element of 70 the airplane, other than the wing (the fuselage for instance) is adapted to be extended.

What is claimed is:—

1. In an airplane, the combination with an airplane wing and a motor, of a radiator for 80 cooling the motor comprising a plurality of radiator cells so organized and related one to the other as to provide separate skin-like cover sections fastened respectively against the upper and lower surfaces of the wing. 85

2. In an airplane, the combination with an airplane wing and a motor, of a radiator for cooling the motor comprising a plurality of radiator cells so organized and related one to the other as to provide a hollow shell of 90 wing profile through the hollow of which the airplane wing is adapted to extend.

3. In an airplane, the combination with an airplane wing and a motor, of a radiator for cooling the motor comprising a hollow shell 95 of wing profile, the walls of the shell being of cellular construction for the purpose of providing for the circulation of a cooling agent therethrough, said shell in its relation to the airplane wing being such that the latter is adapted to pass therethrough without a break in its continuity. 100

4. In an airplane, the combination with an airplane wing and a motor, of a radiator for cooling the motor comprising a plurality 105 of radiator cells so organized and related one to the other as to provide a radiator of wing profile and of hollow section, the shape of the hollow of the radiator being such that that portion of the airplane wing which is 110 adapted to provide its support is adapted also to extend through the hollow of the radiator without a break in its continuity.

5. A wing type radiator for airplanes comprising a cellular structure of wing profile, 115 the structure in cross-section being hollow, whereby the airplane wing, upon which the radiator is mounted, is adapted to pass uninterruptedly through it, the cells collectively providing both a top and bottom covering 120 for at least a portion of the wing.

6. In an airplane, the combination of an airplane wing and a motor, of a radiator for cooling the motor comprising a plurality of radiator cells arranged in parallelism in a 125 fore and aft direction, the cells collectively affording a hollow shell through which the airplane wing is adapted to extend uninterrupted.

7. A wing type radiator for airplanes in- 130

cluding flat plates fastened respectively against opposite sides of the wing framework, and corrugated plates fastened upon the outer face of the flat plates, the plates

5 jointly providing a plurality of radiator cells and at the same time constituting the wing covering.

8. A wing type radiator for airplanes comprising a cellular structure of hollow 10 section and through the hollow of which the airplane wing is adapted to extend substantially uninterruptedly, said wing in the vicinity of the radiator being provided with openings whereby a circulation of air within 15 in the hollow of the shell is obtainable.

9. In an airplane, the combination with an airplane wing and a motor, of a radiator for cooling the motor, comprising a plurality of radiator cells so organized and related one 20 to the other as to provide a hollow shell of wing profile through the hollow of which the airplane wing is adapted to extend, said wing in the vicinity of the radiator being provided with openings whereby a free circulation of air within the hollow shell is 25 permitted.

10. In an airplane, the combination with the motor, of a radiator for cooling the motor comprising a plurality of radiator 30 cells extended in the direction of the air flow over the radiator so organized and related one to the other as to provide a hollow shell through the hollow of which a structural element of the airplane is adapted 35 to extend substantially uninterruptedly, said

hollow shell in its relation to said structural element being such that a bodily removable outer covering for the structural element is provided.

11. In an airplane, the combination with 40 the motor, of a radiator for cooling the motor comprising a plurality of radiator cells so organized and related one to the other as to provide a hollow shell through the hollow of which a structural element of 45 the airplane is adapted to extend, said hollow shell being bodily removable and when in place upon the structural element of the airplane providing its support, being so related thereto as to provide therefor an 50 outer covering impervious to air.

12. In an airplane, a radiator of aerofoil shape, having radiator tubes extending along the upper and lower surfaces thereof, and connections for introducing fluid into and 55 leading it from the radiator.

13. In an airplane, a radiator shaped to serve as a sustaining member, formed in sections adapted to be removably secured together, each section having a compartment 60 at its leading and trailing edges and tubes extending along the upper and lower surfaces of the section connecting said compartments together, and means for introducing fluid to all of the compartments at one edge 65 and leading fluid from all of the compartments at the other edge.

In testimony whereof I hereunto affix my signature.

ARTHUR L. THURSTON.
